UNITED STATES PATENT OFFICE.

ROLLIN C. LEWIS, OF STAMFORD, CONNECTICUT, ASSIGNOR TO YALE & TOWNE MANUFACTURING COMPANY, OF STAMFORD, CONNECTICUT.

COMBINATION DIAL LOCK.

Application filed December 3, 1925. Serial No. 73,006.

To all whom it may concern:

Be it known that I, ROLLIN C. LEWIS, a citizen of the United States, and resident of Stamford, in the county of Fairfield 5 and State of Connecticut, have invented certain new and useful Improvements in Combination Dial Locks; and I do hereby declare the following to be a full, clear, and exact description of the invention, such 10 as will enable others skilled in the art to which it appertains to make and use the same.

This invention relates to improvements in combination dial locks and more particularly to means for changing the combination of the tumblers and for ascertaining the combination of the tumblers in the event of failure to record or remember the same.

With many dial locks as heretofore constructed it has been necessary to take the lock apart and shift the outer tumbler members on their centers or inner tumbler members and then reassemble the lock.

One object of my invention is to provide a simple construction in a dial combination lock whereby the setting or combination of the tumblers may be easily changed without disturbing the lock by dismemberment 30 of any part thereof.

A further object is to provide simple means for re-setting the tumblers to unlocking position, in the event of failure to record or remember the combination.

With these and other objects in view, the invention consists in certain novel features of construction and combination of parts as hereinafter set forth and pointed out in the claims.

In the accompanying drawings;

Figure 1 is a rear face view (showing the rear cap and disk or spider removed) illustrating an embodiment of my invention;

Figure 2 is a similar view, with the rear cover plate and tumbling shifting lever removed;

Figure 3 is a view partly in elevation and partly in vertical section;

Figure 4 is a view of the key;

Figure 5 is a transverse sectional view showing the lock applied to a door;

Figure 6 is a view of one of the tumbler members;

Figure 7 is a view showing certain of

the tumbler-shifting devices and the spindle cam or tumbler;

Figure 8 is a view showing the two parts of the tumbler cage, separated;

Figure 9 is a view showing the casing 60 or curb, the inner tumbler members or centers and the sleeve on which latter are mounted;

Figure 10 is a plan view showing the fence and resetting lever, and 65

Figure 11 is a separate view, in perspective, of the resetting lever.

In the drawings, a fragmentary part of a door is indicated at 1, and to the rear face of the same, the casing or curb 2 of the 70 lock is secured, the latter having a fence opening 2^a. A sleeve 3 enters the casing and has threaded connection with the front wall thereof. This sleeve passes through a suitable hole in the door and is threaded 75 to receive nuts 4, 5, between which the web of a dial ring or escutcheon 6 located on the outer face of the door, is disposed. A dial 7 is rotatable within the annular flange of the escutcheon and is provided with a hub 80 mounted to turn in the outer end portion of the sleeve 3.

One end of a spindle 9 is screwed or otherwise secured to the dial hub 8 and extends through the sleeve 3. The rear end of said 85 spindle terminates within the casing 1 and is threaded to receive the elongated hub 10 of a spindle cam or tumbler 11, the latter being normally secured against rotation on said spindle by means of a key 12, and said 90 cam or tumbler 11 is made with a gating 13 to receive a finger on the fence, as hereinafter explained.

The rear end portion of the sleeve 3 which is disposed within the casing 1 is made with 95 an annular groove or recess which provides a mounting on said sleeve for the inner members or centers 14 of a plurality of tumblers. Each of these tumblers includes outer annular tumbler members 15 having toothed 100 inside portions to mesh with similar teeth on the peripheries of the inner tumbler members or centers 14, whereby the inner and outer tumbler members are normally interlocked and caused to rotate together, and the 105 outer tumbler members 15 are provided with gatings 16 to receive the fence. The spindle tumbler 11 is cooperable with one of the inner tumbler members and the several tumbler members 14 are cooperable with each 110

other in a manner to effect the setting of the tumblers when the dial is manipulated in accordance with a predetermined combination to align the tumbler gatings to receive the fence, but as these details do not constitute part of my present invention, further description thereof herein are unnecessary.

The outer tumbler members 15 are mounted to turn in grooves 17 in a cage 18. This cage is made in two parts 18^a, 18^b, and the latter is provided with an opening 19 to permit access of the fence 20 to the tumbler gatings. The fence 20 is pivotally mounted at 21 and its hook-shaped end 22 is adapted to enter the tumbler gatings 16, a portion of the hook-shaped part 22 being extended to form a finger 23 to enter the gating 13 of the spindle tumbler 11. The tail portion of the fence 20 is heavier than the hook-shaped portion 22, so that the latter is normally pressed lightly against the tumblers and when the gatings of the latter are not in alignment, the tail of the fence will be in the path of movement of the bolt member indicated at 24, and thus the bolt work will be locked. When the tumblers shall have been set by manipulation of the dial, so that their gatings shall be properly positioned, the fence will move by gravity, the hook-shaped portion 22 thereof entering the tumbler gatings and the tail portion of said fence dropping out of the path of the bolt member 24, thus unlocking the bolt-work and permitting the latter to be manually operated in the usual manner.

The tumbler cage 18 is mounted so that it may be slid longitudinally within the casing 1 for the purpose of moving the tumbler members 15 out of intermeshing relation with the inner tumbler members or centers 14, when the "combination" is to be changed and for moving said tumbler members 15 to their normal positions in mesh with the inner members 14 when the "combination" shall have been changed. The rear portion of the cage 18 is contracted somewhat in inside diameter and is provided with an interior screwthread 25 which receives the exteriorly threaded portion of a cage-moving member or annular nut 26. This member 26 is made with a tubular hub or sleeve 27 which passes freely through a hole in the back cover plate 1^a of the casing 1 and said hub or sleeve is made with an annular series of notches 28 and an annular groove 29. A lever 30 disposed against the rear face of the cover plate 1^a is made with an opening for the accommodation of the hub or sleeve portion 27 of the member 26 and the inner wall of said opening is notched as at 31 (Fig. 1) to permit the lever to be passed over the lugs formed by the notches 28 of the hub or sleeve 27 and enter the annular groove 29 of the latter. A ring or disk 32 is located against the lever 30 and is provided with laterally

projecting lugs 33 which pass through certain of the notches 28 in the hub or sleeve 27 and enter certain of the notches 31 in the lever 30. The lever 30 is thus connected with the cage-moving member 26 so that when said lever is moved, said member 36 will be turned to effect longitudinal movement of the cage 18 and the tumbler members 15 carried thereby. The rear end of the tubular hub or sleeve 27 is closed by a cap 27^a having threaded connection with the same. When the parts are in their normal positions, the cage-moving member 26 is prevented from rotation by means of a locking spring 34. This spring is provided at its respective ends with pins or projections 35 and 36, the former entering a socket 35^a in a flange 37 of the cage and the pin or projection 36 passing through a hole in said flange and entering a socket 36^a in the threaded peripheral portion of the member 26.

The rear cover plate 1^a is provided with two holes 38 for the accommodation of a two-armed key 39, and for the same purpose, the cage 18 is provided with holes 40 at the top and bottom of the fence opening 19 of the cage,—the holes 38 and 40 being so located that when the arms of the key is passed through them, said arms will also pass through aligned gatings 16 of the tumbler members 15 and retain said tubular members against being turned, said key also serving as guiding means for the cage when the latter is moved longitudinally. When the key is inserted, the end of the finger 23 of the fence may be resting against the peripheral face of the spindle cam or tumbler 11, and in order that the hook-shaped end of the fence may be moved outwardly when the key is inserted, the fence finger 23 is provided with a cam notch 41 which will be engaged by one of the arms of the key.

It will be observed by reference to Fig. 2 that that portion of the locking spring which is adjacent to the pin or projection 36^a at one end of said spring, passes across one of the key holes 40 in the cage, and that the free ends of the arms of the key 39 are beveled as indicated at 42, Fig. 4. Now when the key is being inserted, the beveled end 42 of one of its arms will engage the locking spring and so move the same as to retract the pin or projection 36 from the socket 36^a in the cage-moving member 26, thus releasing the latter so that it may be turned.

When the dial shall have been properly manipulated to align the gatings of the tumbler 15, the operation of changing the "combination" may be proceeded with as follows:

The two armed key 39 will first be inserted as previously explained and will hold the tumbler members 15 with their gatings in alignment when said tumbler members

are moved out of intermeshing relation to the inner tumbler members or centers 14. Normally, the arm of the lever 30 is disposed at one side of the key openings 38. The 5 key having been inserted, the operator will turn the lever 30 so that its arm will become disposed at the opposite side of the inserted key. During this movement of the lever, motion will be imparted to the member 26 and, by reason of the threaded connection of said member with the cage 18, the latter will be moved longitudinally within the casing 1, carrying with it, the outer tumbler members 15 out of mesh with 10 the inner tumbler members or centers 14. The inner tumbler members or centers 14 may now be turned independently of the tumbler members 15, by manipulation of the dial. The "combination" may now be 15 changed by turning the dial from number to number of the new combination, but care should be exercised not to make the final turn of the dial which would bring the gatings of the spindle cam or tumbler into alignment with the gatings of the tumbler members 15. The lever 30 may now be swung back to normal position with its arm at the left of the key and the latter then withdrawn. The lock is now reset and must be 20 operated upon the new combination.

Provision is also made to facilitate the resetting of the tumblers in the event of failure to record or to remember the new combination. To this end, a resetting lever 35 43 is mounted on the pivot pin 21 of the fence. This lever includes spaced arms 44, and the forward end of the fence is made with a slot 45 for the accommodation of one 40 of said arms. This slot 45 may be formed with the use of a separate plate 46 riveted to the fence and extended to form the fence finger 23. The lever 43 is provided with two stepped cross bars 47 adapted to be made to engage the tumbler members 15, and a handle 48 is provided on said lever to facilitate its manipulation. The rear cover 45 plate 1^a may be provided with a notch 49 to receive the lever handle and thus permit the stepped cross bars to properly reach 50 the tumbler members 15.

To pick up the combination, the operator will press the lever 43 upward lightly and then turn the dial in the same manner as when setting up any combination. Upon 55 turning the dial anti-clockwise, the lever will drop into the gating of the first tumbler member 15, and then by turning the dial clockwise, the lever will pick up the second tumbler member 15, and then by turning the 60 dial anti-clockwise, the lever will engage the third tumbler member 15. The resetting lever 43 will then be released and the dial turned clockwise to position the gating 13 of the spindle cam or tumbler 11. The lock 65 may now be again reset to the desired com-

bination, in the manner previously described.

Having fully described my invention what I claim as new and desire to secure by Letters-Patent, is:—

1. In a combination lock, the combination 70 with a casing, a dial spindle, inner tumbler members operable by rotation of the dial spindle, and outer tumbler members normally having intermeshing connection with said inner tumbler members, of a cage movable longitudinally in the casing and provided with mountings for the outer tumbler members, and a cage-moving member supported by the casing and having threaded connection with the cage to effect longitudinal movement of said cage to disconnect the outer from the inner tumbler members when said member is turned, said member being accessible outside the casing for 75 manual operation.

2. In a combination lock, the combination 80 with a casing, a dial spindle, inner tumbler members operable by rotation of the dial spindle, and outer tumbler members normally having intermeshing connection with said inner tumbler members, of a cage movable longitudinally in the casing and provided with mountings for the outer tumbler members, a cage moving member supported 85 by the casing and having cooperative relation to the cage to effect longitudinal movement of said cage to disconnect the outer from the inner tumbler members when said member is turned, said member being accessible for manual operation, and a lever outside the casing for turning said cage-moving member.

3. In a combination lock, the combination 90 with a casing, a dial spindle, inner tumbler members operable by rotation of the dial spindle, and outer tumbler members normally having intermeshing connection with said inner tumbler members, said outer tumbler members having gatings, of a longitudinally movable cage carrying the outer tumbler members, a cage-moving member carried by the casing and accessible from outside thereof for manual operation, said member having threaded connection with 95 said cage, and a key insertable into the casing and adapted to pass through the gatings of the outer tumbler members to hold the latter from turning.

4. In a combination lock, the combination 100 with a casing, a dial spindle, inner tumbler members operable by rotation of the dial spindle, and outer tumbler members normally having intermeshing connection with said inner tumbler members, said outer 105 tumbler members having gatings, of a longitudinally movable cage carrying the outer tumbler members, a cage-moving member carried by the casing and accessible from outside thereof for manual operation, said member having threaded connection with 110

said cage, and a key insertable into the casing and adapted to pass through the gatings of the outer tumbler members to hold the latter from turning, said cage also having 5 holes for the passage of said key, whereby said key may serve as guide means for the cage when the latter is moved longitudinally.

5. In a combination lock, the combination 10 with a casing, a dial spindle, inner tumbler members operable by rotation of the dial spindle, and outer tumbler members normally having intermeshing connection with said inner tumbler members, said outer 15 tumbler members having gatings, of a longitudinally movable cage carrying the outer tumbler members, a cage-moving member carried by the casing and accessible from outside thereof for manual operation, said 20 member having threaded connection with said cage, a key insertable into the casing and adapted to pass through the gatings of the outer tumbler members to hold the latter from turning, said cage also having holes 25 for the passage of said key, whereby said key may serve as guide means for the cage when the latter is moved longitudinally, spring actuated locking means for said cage-moving member, said locking means normally 30 extending across a key opening in the cage and operable by insertion of the key to unlock cage-moving member from locked relation to the cage.

6. In a combination lock, the combination 35 with a casing, a dial spindle, inner tumbler members operable by rotation of the dial spindle, and outer tumbler members normally having intermeshing connection with said inner tumbler members, said outer tumbler 40 members having gatings, of a longitudinally movable cage carrying the outer tumbler members, a cage-moving member carried by the casing and accessible from outside thereof for manual operation, said member having 45 threaded connection with said cage, a key insertable into the casing and adapted to pass through the gatings of the outer tumbler members to hold the latter from turning, and a fence having a beveled portion to 50 be engaged by the key to force the fence outwardly.

7. In a combination lock, the combination 55 with a casing including a rear cover plate, a dial spindle, inner tumbler members operable by rotation of the dial spindle, a longitudinally movable cage within said casing, outer tumbler members carried by said cage and normally having intermeshing connection 60 with the inner tumbler members, said cage having interior screw threads, a cage-moving member entering the cage and having a threaded portion meshing with the

threads in said cage, said member having a notched hub passing through the rear cover plate of the casing, a notched lever mounted on said hub and accessible exteriorly of said cover plate, and a ring encircling said hub and having lugs to engage the notched lever and notches of the hub to lock said lever to the hub of said cage-moving member.

8. In a combination lock, the combination 65 with a casing, a dial, and a dial ring, of a sleeve entering said casing and secured thereto, a nut threaded on said sleeve and engaging the dial ring, a spindle secured to the dial and passing through said sleeve, a spindle cam or tumbler secured to said spindle within the casing, inner tumbler members mounted on said sleeve and operable by the turning of the spindle and the cam or tumbler secured thereto, a cage longitudinally movable in the casing, outer tumbler members carried by said cage and normally having intermeshing connection with the inner tumbler members, and means for moving 70 said cage longitudinally to move the outer tumbler members out of or into intermeshing connection with the inner tumbler members.

9. In a combination lock, the combination 75 with a casing, a dial, a dial spindle, and tumblers having gatings, of a pivoted manually operable resetting lever having a stepped portion for cooperation with said tumblers to enter the tumbler gatings successively when the dial is manipulated and effect alignment of the gatings.

10. In a combination lock, the combination 80 with a casing, a dial, a dial spindle and tumbler members, of a fence to enter gatings of the tumbler members, and a manually operable stepped resetting lever associated with said fence and cooperable with the tumbler members to align their gatings when the dial is manipulated.

11. In a combination lock, the combination 85 with a casing, a dial, inner tumbler members, operative connections between said tumbler members and the dial, and outer tumbler members normally having intermeshing connection with the inner tumbler members, of means for moving the outer tumbler members out of operative connection with the inner tumbler members whereby the combination of the tumblers may be changed said means being also operable to move said outer tumbler members into operative relation with the inner tumbler members, and a resetting device cooperable with said outer tumbler members to set their gatings when the dial is manipulated.

120 In testimony whereof, I have signed this specification.

ROLLIN C. LEWIS.
